CLAIM

The ornamental design of a laptop port, as shown and described.

DESCRIPTION

FIG. 1 is a pictorial view, taken from the top, right side, and rear of a laptop port showing our new design;

FIG. 2 is a front elevational view thereof;

FIG. 3 is a rear elevational view thereof;

FIG. 4 is a top view thereof;

FIG. 5 is a right side elevational view thereof, the left side elevational view being a mirror image thereof;

FIG. 6 is a fragmentary view similar to FIG. 5;

FIG. 7 is similar to FIG. 2 but adding, in broken line, environmental subject matter which is not part of our claimed design; and,

FIG. 8 is a bottom view of the FIG. 1 design.

Throughout the drawings, broken lines depict environmental subject matter which is not part of our claimed design.
